UNITED STATES PATENT OFFICE

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS

PORTABLE AUTOGRAPHIC REGISTER

Application filed May 7, 1931. Serial No. 535,757.

This invention relates particularly to autographic registers, and more particularly to autographic registers employing flat zig-zag folded stationery drawn from a supply 5 packet beneath the platen of the machine.

The primary object is to provide a light, portable register of improved construction and operation, which may be carried conveniently by expressmen, inspectors, and the 10 like.

A preferred embodiment of the invention is illustrated in the accompanying drawings, in which—

Fig. 1 is a perspective view of a register 15 embodying the invention; Fig. 2, a front end view of the machine; Fig. 3, a longitudinal vertical sectional view; Fig. 4, a broken transverse vertical sectional view, taken as indicated at line 4 of Fig. 3; and Fig. 5, a 20 broken perspective view of one of the guide blades showing how the carbon is held thereby.

In the embodiment illustrated, A designates a casing having a platen A', a supply- 25 compartment A², and a record or filing-compartment A³; B, a guide and carbon supporting device; and C, a clamping-bar adapted to hold the front ends of the stationery against the platen.

The platen A' is fixedly mounted on the upper flanged portion of the sidewalls of the supply compartment A². The platen extends forwardly and laterally over the casing A and marginal side portions 10 are 35 struck downwardly to form flanges which strengthen the structure.

The base and side walls of the supply compartment A² may be formed from a single piece of sheet metal, preferably aluminum, 40 the sidewalls 11 being struck upwardly from the base portion 12, and outwardly at 13 to form the flanges to which the platen is attached. The front end wall 14 is curved upwardly to meet the platen. The rear of the 45 compartment is left open and a guide-roll 16 journaled in the upper rear corner portions of the sidewalls of the compartment.

The base and sidewalls of the record-compartment A³ also may be formed from sheet metal, the sidewalls 17 being struck upwardly

from the base 18 and adapted to fit around the compartment A² and connected thereto by pivots 19. The front of the compartment is left open to admit slips, and the rear wall 20 is turned upwardly and extends somewhat 55 higher than the sidewalls, so as to partially enclose the rear of the supply-compartment. A stop 21 limits the swing of supply-compartment into the record-compartment, which is held therein by hooks 22 and eyes 60 23. If desired, slip-retaining means (not shown) may be provided for the front end of the record compartment.

A guide device B comprises a stack of thin resilient blades or guide-bars 25 which are 65 pivotally supported at one end by a capped guide-post 26 and at the other by an inverted U-shaped keeper 27, which is fastened to the flange 10 of the platen by means of a rivet 28. Spacing washers 25^a provide room for 70 the stationery between the bars. The bars may be arched or bent upwardly out of the keeper, as indicated by the dotted lines in Fig. 4, and swung forwardly out of the path of the paper webs 30. This method of supporting the guide-bar has been found satisfactory but any suitable means may be employed. As indicated in Figs. 3 and 5, carbon sheets 31 are held in position by folding the rear edge of a sheet back over one of the 75 guide-bars 25. This fold is sufficient to prevent the sheet from being drawn forward with the webs 30, when the latter are advanced over the platen. If desired, the end of the sheet may be given an additional half 80 turn about the bar to prevent any displacement of the sheet in case the webs are drawn backwards slightly, but ordinarily this additional fold is not necessary. It will be noted that the top guide-bar is superposed above 90 all the sheets and webs to hold them against the platen in close relation. This relation has been exaggerated in the drawings to show the stationery more clearly.

The web-gripping bar C is U-shaped and 95 extends through a pair of perforations in the front portion of the platen. The central portion 35 of the bar is offset to provide a finger-grip and the extremities of the bar are threaded and provided with springs 36 and 100

nuts 37, which urge the bar against the platen with an adjustable pressure. The carbon sheets are not long enough to reach the bar, and the webs are provided with lines of 5 weakening 30^a, along which the webs may be torn in advance of the bar C. The front edge of the platen is provided with a notch 38 to facilitate taking hold of the ends of the webs.

10 The register is loaded by unlatching the hooks 22 and opening the compartment A² and inserting a packet of paper webs. All of the guide-bars 25 are sprung out of the keeper 27 and swung forwardly to permit the 15 bottom web to be laid over the platen. The lower guide-bar is then positioned over the lower web and a carbon sheet folded over the bar, as shown in Fig. 3, so as to extend forwardly with the webs. The remaining webs 20 and carbon sheets are similarly positioned, seriatim, and the top bar sprung into place. After the ends of the webs have been adjusted to uniform length and slipped under the bar C, the register is ready for use. When 25 a form has been filled in a fresh one is drawn forward and the completed one severed. As many copies as desired may be placed in the compartment A³. When the carbon sheets become worn they may either be renewed, the 30 length of fold increased, or the sheets turned end for end. The latter expedients will effect a considerable saving in carbon-paper.

It will be noted that by holding the carbon in this manner, the carbon-sheets are 35 completely covered by the paper webs and protected from soiling, wetting, tearing, or like abuse, which would shorten their period of usefulness.

The foregoing detailed description has 40 been given for clearness of understanding only and no unnecessary limitations should be understood therefrom, but the appended claims should be construed as broadly as permissible, in view of the prior art.

45 What I regard as new, and desire to secure by Letters Patent, is:

1. In an autographic register: an open-top filing-compartment having a slip-admitting opening and an upwardly extending rear 50 wall; and a movably mounted unit forming a closure for said filing-compartment, comprising a supply-compartment partially enclosed by the rear wall of said filing-compartment, a surmounting platen equipped at 55 its front end with a stationery gripping-bar, and a guide near the rear of said platen through which stationery may be drawn from said supply-compartment over the platen, said guide being adapted to hold carbon 60 sheets and prevent them from advancing forwardly with said stationery.

2. In a register: a supply-compartment; a platen; laterally spaced guide-supports between which paper webs may be drawn over 65 said platen; and a device comprising a stack

of spaced thin resilient flat carbon-supporting bars pivoted at one end to one of said guide-supports, the other guide-support having catch-devices to engage the free ends of said bars.

70 LOUIS JENSEN.
